(57) **CLAIM**

The ornamental design for a stand for display screen as shown and described.

DESCRIPTION

1.1 : Perspective view thereof in a first state

1.2 : Rear perspective view thereof

1.3 : Front elevation view thereof

1.4 : Rear elevation view thereof

1.5 : Left side elevation view thereof, the right elevation view is a mirror image thereof

1.6 : Top plan view thereof

1.7 : Bottom plan view thereof

1.8 : Enlarged view taken from **1.2**

1.9 : Rear perspective view thereof with a display screen environment of use

1.10 : Rear perspective view thereof with another display screen environment of use

1.11 : Left side elevation view in a first rotation state, the right elevation view is a mirror image thereof

1.12 : Left side elevation view in a second rotation state, the right elevation view is a mirror image thereof

1.13 : Left side elevation view in a third rotation state, the right elevation view is a mirror image thereof

1.14 : Top plan view in a fourth rotation state

The evenly spaced broken lines depict portions of the article that form no part of the claimed design. The dot-dash line

(Continued)

and adjoining curvy line illustrate the bounds of the enlarged view and form no part of the claimed design. The broken lines form no part of the claimed design.

1 Claim, 14 Drawing Sheets
